TURRET LATHE TOOL

Michael W. Papp, Cleveland, Ohio, assignor to The
Warner & Swasey Company, Cleveland, Ohio, a corpora-
tion of Ohio

Filed Jan. 14, 1966, Ser. No. 607

Term of patent 14 years

(Cl. D54—6)

FIG. 1

FIG. 2

FIG. 3

FIG. 4

FIG. 1 is a perspective view of a turret lathe tool taken from the front and righthand side, embodying my new design;

FIG. 2 is a perspective view thereof, showing the front and left hand side;

FIG. 3 is a perspective view thereof, showing the rear and one side; and

FIG. 4 is a perspective view thereof, showing the bottom and one side.

The dot-dash lines shown on the drawing are for illustrative purposes only.

What I claim is:

The ornamental design for a turret lathe tool, substantially as shown and described.
